UNITED STATES PATENT OFFICE.

JESSIE C. TAYLOR, OF TORONTO, CANADA.

DESIGN FOR A DRESSING-CABINET.

SPECIFICATION forming part of Design No. 35,956, dated June 17, 1902.

Application filed December 3, 1901. Serial No. 84,591. Term of patent 3½ years.

To all whom it may concern:

Be it known that I, JESSIE CAMPBELL TAYLOR, a British subject, residing at Toronto, in the county of York and Province of Ontario, 5 Canada, have invented and produced a new and original Design for Dressing-Cabinets, of which the following is a specification, reference being had to the accompanying drawings, in which—

- o Figure 1 is a perspective view of the dressing-cabinet looking at it from the front, and Fig. 2 is a similar view looking at it from the back, these two views being deemed necessary to fully illustrate the design.
- 5 The leading feature of my design consists in the arrangement of the parts and the general appearance of the dressing-cabinet.

In the front *a* of the dressing-cabinet is a rectangular mirror *b*, and at each side of the

mirror are ornamental shelves *c*. Located 20 below the shelves *c* is an ornamental locker *f*. The base *g* projects beyond the front *a*, and the front and back of the base are provided with drawers *h* and lockers *i*. The dressing-cabinet is surmounted by an ornamental top 25 *k*. The upper part of the back of the cabinet is open, and at the back of the front *a* is a mirror *l*. At each side of the mirror *l* is a locker *m*, and below each of the lockers *m* is a towel-rack *o*, and below the towel-racks *o* are 30 shelves *p*.

What I claim is—

The design for the dressing-cabinet herein shown and described.

JESSIE C. TAYLOR.
